Primary Examiner — Eric Goodman*Assistant Examiner* — Katherine Holbrow(74) *Attorney, Agent, or Firm* — Winston Hsu; Scott Margo(57) **CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a second embodiment thereof; FIG. 3 is a front view of a third embodiment thereof; FIG. 4 is a front view of a fourth embodiment thereof; and, FIG. 5 is a front view of a fifth embodiment thereof.

The dot-dash lines showing a portion of a display screen in the figures are included for the purpose of illustrating portions of the article and form no part of the claimed design. The broken lines showing text and other elements in the figures are included for the purpose of illustrating portions of the article and form no part of the claimed design.

1 Claim, 5 Drawing Sheets(56)
